DESCRIPTION

See application file for complete search history.

FIG. 1 is a perspective view of a vertical shaft impact crusher rotor floor showing our new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a plan view thereof; and,

FIG. 7 is a bottom view thereof.

The broken lines are for the purpose of showing environmental structure, and form no part of the claimed design.
